UNITED STATES PATENT OFFICE.

MILON J. TRUMBLE, OF ALHAMBRA, CALIFORNIA.

STEAM-BOILER.

1,361,931.

Specification of Letters Patent. Patented Dec. 14, 1920.

Application filed May 26, 1919. Serial No. 299,970.

To all whom it may concern:

Be it known that I, MILON J. TRUMBLE, a citizen of the United States, residing at Alhambra, in the county of Los Angeles and State of California, have invented a new and useful Steam-Boiler, of which the following is a specification.

My invention relates to steam boilers, and more particularly to steam boilers which 10 are adapted to be used in automobiles or other vehicles.

The principal object of my invention is to provide a steam boiler which will be very light in weight and which will be very 15 strong in proportion to its weight. Further objects and advantages will be made evident hereinafter.

Referring to the drawings which are for 20 illustrative purposes only,

Figure 1 is a side elevation of my invention.

Fig. 2 is a section on line 2—2 of Fig. 1.

Fig. 3 is a side elevation of one of the stay rivets.

In the form of the invention illustrated 25 in the drawing, a fire box 11 is provided having a burner 12 in the bottom thereof and a flue 13 in the top. Secured inside the fire box 11 is a cylindrical jacket 15 and 30 secured inside this jacket in spaced relationship therewith is a shell 16. The jacket 15 and shell 16 are secured to an outer annular head 17 at the top and bottom thereof, the jacket and shell being welded there- 35 to, and the ends of the space inside the shell being closed by heads 18 also welded in place.

Rigidly secured between the shell 16 and the jacket 15 at frequent intervals are rivets 40 20; these rivets having the form shown in Fig. 3 and consisting of a central portion 21 and ends 22 of smaller diameter. These rivets are secured in drilled holes in the shell 16 and jacket 15 and are riveted over 45 and welded. It will be noted that the members 15, 16 and 17 form a rigid and extremely strong member when complete, and that the members 20 form heat conducting 50 members assisting in delivering the heat of combustion to the water as will hereinafter be explained.

Located inside the shell 16 are four induction tubes 30, these tubes being connected into the space between the shell 16 and the jacket 15, hereinafter called the preheat- 55 ing space, and extending downwardly to a point near the bottom head 18. Secured in the head 18 in gas tight relationship therewith are fire tubes 31. A water pipe 33 is connected into the space between the shell 60 16 and the jacket 15 and a steam outlet pipe 35 is connected into the top of the boiler, being secured in gas tight relationship in the head 18. Water being delivered through the pipe 33 passes upwardly between the 65 shell 16 and the jacket 15, being heated by its contact with the jacket 15 which in turn is heated by the hot gas delivered by the burners 12. As previously explained, the rivets 20 serve to conduct heat from the 70 jacket 15 and deliver it to the water. This water is finally delivered through the induction tubes 30 to the bottom of the boiler near the header 18. The hot gases of combustion also pass upwardly through the fire 75 tubes 31, being taken off through the flue 13, the body of water and steam around the tubes 31 being heated by these hot gases. Steam is drawn off through the pipe 35 and delivered to any type of engine to which 80 the inventor desires to connect it.

I claim as my invention:

A steam boiler comprising a jacket; a cylindrical shell concentrically located inside said jacket; rivets radially placed and connecting and staying said jacket and shell together; annular heads closing the ends of the space between the shell and the jacket; means for introducing water into said space; circular heads closing the cylindrical steam 90 space inside said shell; fire tubes passing through said cylindrical steam space parallel to the axis of said space; an induction tube connected into the top of the space between said shell and said jacket and delivering 95 fluid to the bottom of the steam space and means for withdrawing steam from said space.

In testimony whereof I have hereunto set my hand at Los Angeles, California, this 100 16th day of May, 1919.

MILON J. TRUMBLE.
